UNITED STATES PATENT OFFICE

WILLIAM H. BRETT, OF SHAKER HEIGHTS VILLAGE, OHIO, ASSIGNOR TO THE ENAMEL PRODUCTS COMPANY, OF CLEVELAND, OHIO, A CORPORATION OF OHIO

APPARATUS FOR FORMING FLANGES

Application filed February 28, 1931. Serial No. 519,074.

This invention, as indicated, relates to apparatus for forming flanges. More particularly it comprises apparatus for forming a reversely curved flange and suitable corner portions adjacent one edge of a table leaf which will permit the same to fit closely against a sheet metal table top when moved to horizontal position, and which will hang in close relation to the edge of the table top when dropped to vertical position.

The table top and leaf formed with the apparatus herein disclosed has been made the subject matter of my copending application for United States Letters Patent, Serial No. 15 470,023, filed July 23, 1930.

It is customary to form the edges of the table top with outwardly curved flanges. It is desirable that the leaf or leaf portions frequently attached to a table have similar outwardly curved flanges and the sides and outer edge. The inner flange of the leaf, however, at the point where it joins the table top should fit closely against the adjacent flange of the table top. This requires that 25 the flange portion of the leaf at the point where it joins the table top must be reversely curved and merge with flanges at each of the sides of the table top which are outwardly directed. In order to properly provide for 30 the displacement of the metal in the outwardly directed flanges at the meeting point with the reversely curved or inwardly directed flange, I provide for a corner construction wherein the meeting flanges merge in a surface directed downwardly and outwardly, and with but slight curvature. Such corner can be produced so as to present a smooth 35 satisfactorily appearing surface, notwithstanding the fact that the outer sides of the table leaf are inclined downwardly and outwardly and the inner edge of the table leaf is inclined downwardly and inwardly.

The invention includes the apparatus for producing a table leaf having a flange and corner construction of the character described. To the accomplishment of the foregoing and related ends, said invention, then, consists of the means hereinafter fully described and particularly pointed out in the 50 claims.

The annexed drawings and the following description set forth in detail certain means and one mode of carrying out the invention, such disclosed means and mode illustrating, however, but several of various ways in which 55 the principle of the invention may be used.

In said annexed drawings:

Fig. 1 is a top plan view showing in assembled relation the stationary and movable die members for producing a reversely directed rearward flange for a table leaf, or like structure, and the corner elements associated therewith; Fig. 2 is a front elevation of the device shown in Fig. 1; Fig. 3 is a plan view of the under side of the presser plate and associated cams; Fig. 4 is a fragmentary sectional view illustrating the cooperative action of the upper plate-carrying cam members and presser plate; Fig. 5 is a view similar to that of Fig. 4, further illustrating the action of the cam members; Fig. 6 is a perspective view showing the actuating member for the corner die members; Fig. 7 is a perspective view of the corner die member; and Fig. 8 is a fragmentary perspective view illustrating a 75 corner of a table leaf, or the like, after being pressed into final form in an apparatus of the character illustrated.

As will appear from the drawings, the apparatus comprises a base plate 1 carrying the stationary portions of the die including a rigidly attached flange forming element 2 and a rearward abutment 3 suitably channeled to provide separate passageways for slides 4 for actuating the movable 80 corner elements 5 of the lower die. The slide is preferably of the shape shown in Fig. 6 and carries an upstanding lug 6 at one end offset from one side of which is mounted a roller 7. The slide carries an integral block 8 on its upper side at the opposite end, said block providing a cam surface 9 on one side substantially in line with said roller. The cam surface 9 is adapted to bear against a cam block 10 to which is secured the inner 95 corner member 5. The cam block 10 is held in retracted position by means of a spring 11 seated in a recess within a lower block. Through the action of the slide and the cam face 9 on its block 8 against the cam face 100

on the block 10, the corner pieces 5 may be projected forwardly within the sheet metal member to snugly fit the corners and align the front edges of said corner pieces 5 with the stationary die member 2 secured to the block.

Cooperating with the stationary member 2 and the corner blocks are sliding die members 13 and 14 (see Figs. 4, 5), secured to a supporting plate 15, said plate having at its rearward edge a plurality of cam faces 16 with which the cam elements on the cam plate, hereinafter to be described, coact. At each of the corners of said movable die are provided cooperating die members 17. These die members are adapted to form the corners of the sheet after the inner corner die members have been forced into place through the operation of the slides. Said movable die members 17 are guided between rigid plates 18, 19 at the respective sides of the supporting plate. Cam faces 21 are provided on the movable die members adapted to be acted upon by the cams hereinafter described.

The construction of the members of the cam plate for actuating the several elements heretofore mentioned will be more readily understood by reference to Figs. 3 to 5 inclusive. Said plate comprises a body member 22 having guide bearings 23 at its inner corners and carrying a presser plate 24 provided with compression springs 25, and also carrying a plurality of cams. These cams, as will be noted by reference to Figs. 2 to 5 inclusive, are of several different lengths, the longest pair 26 adjacent the outer edges of the plate serving to engage the rollers 7 on the slide blocks and through the associated elements to force the corner dies into alignment with the inner die plate. The second series of cams 27 are so formed as to move the slide die plates 13 and 14 into contact with the depending flange across substantial- ly the entire edge of the metal sheet being worked upon. The remaining cams 28 are disposed at the extreme corners of the cam plate and coact with the sliding die members 17 which, in conjunction with the inner die members 5, form a special corner configuration which merges the inwardly and outwardly inclined flanges.

As is clearly shown in Fig. 1, the plate 15 carrying the movable die members 13, 14 is normally held in spaced relation to the rigid die member 2 by means of a series of springs 29.

From the description of the construction of the apparatus its operation will be readily understood. The metal sheet or plate 30 which it is desired to provide with a reverse- ly curved flange is first formed with a plain downwardly extending flange around the margin of the plate. The flanges at front and side edges of the plate are then formed

into downwardly and outwardly directed flanges having an inwardly directed extension flange at the free edge. The metal so formed is then placed with the intermediate plain flange over the rigid die member 2 and the corner die elements 5 are then forced outwardly into close fitting relation with the inner corners of the plate. As the cam slide is further depressed, the outer die members 13 and 14 are brought into contact with the depending flange of the plate which is formed into a reversely curved member of the configuration shown in Figs. 4 and 5. The further depression of the plate carrying the cams actuates the corner dies 17 and causes the formation at each end of the metal sheet, of a corner such as is illustrated in Fig. 8 wherein the downwardly and inwardly directed flange 32 merges along the corner surface 33 into a flange 31 having a downwardly and outwardly directed inclination.

Other modes of applying the principle of my invention may be employed instead of the one explained, change being made as regards the means and the steps herein disclosed, provided those stated by any of the following claims or their equivalent be employed.

I therefore particularly point out and distinctly claim as my invention:

1. An apparatus of the character described having in combination a stationary die member adapted to underlie the central portion of a metal plate beneath the front edge thereof, said plate having a plain downwardly directed flange and downwardly and outwardly extending flanges at its respective side edges, angularly movable corner die members, means for moving said corner die members into alignment with the front edge of said stationary die member, a companion die member positioned adjacent said stationary die member, means for moving the same into flange shaping relation with said stationary die member, complementary die members positioned adjacent said stationary die member, and means for moving the same into corner shaping relation with said corner die members.

2. An apparatus of the character described having in combination a bed plate, a stationary die member secured to said bed plate and adapted to underlie the central portion of a metal plate beneath the front edge thereof, said plate having a plain downwardly directed flange and downwardly and outwardly extending flanges at its respective side edges, angularly movable corner die members positioned on said bed plate closely adjacent the ends of said stationary die member, means for moving said corner die members into alignment with the front edge of said stationary die member, a companion die member positioned adjacent said stationary die member and complementary die members positioned adjacent said corner die members, an

upper plate adapted to be moved toward said base plate, means carried by said upper plate adapted to clamp the work to said base plate and to actuate said movable die members into 5 flange shaping relation with said companion members.

3. An apparatus of the character described having in combination a bed plate, an upper plate vertically movable above said bed plate, 10 a stationary die member secured to said bed plate and adapted to underlie the central portion of a metal plate beneath the front edge thereof, said plate having a plain downwardly directed flange and downwardly and outwardly extending flanges at its respective side edges, angularly movable corner die members positioned on said bed plate closely adjacent the ends of said stationary die member, means for moving said corner die members into alinement with the front edge of 20 said stationary die member, a companion die member positioned adjacent said stationary die member and complementary die members positioned adjacent said corner die members, 25 a resiliently supported presser plate associated with said upper plate and a plurality of cam members mounted on said upper plate and adapted to actuate the movable die members.

30 4. An apparatus of the character described having in combination a bed plate, an upper plate vertically movable above said bed plate, a stationary die member secured to said bed plate and adapted to underlie the central portion 35 of a metal plate beneath the front edge thereof, said plate having a plain downwardly directed flange and downwardly and outwardly extending flanges at its respective side edges, angularly movable corner die members positioned on said bed plate closely adjacent the ends of said stationary die member, means for moving said corner die members into alinement with the front edge of 40 said stationary die member, a companion die member positioned adjacent said stationary die member and complementary die members positioned adjacent said corner die members, a resiliently supported presser plate associated with said upper plate and a plurality of 45 cam members mounted on said upper plate and adapted to actuate the movable die members successively to shape the central portion of the flange and the corner portions thereof.

50 5. An apparatus of the character described having, in combination, a base plate, stationary and movable die members mounted on said base plate for shaping the central and corner portions of a sheet metal flange, said 55 movable die members including corner shaping elements associated with said stationary die member, means for moving said corner shaping elements angularly with respect to said stationary die member, flange shaping die members each having a cam face posi-

tioned adjacent said stationary and corner die members, and a series of cams for successively engaging the cams on said die members and moving them into flange shaping relation with said first named die members. 70

Signed by me this 10th day of January, 1931.
